UNITED STATES PATENT OFFICE.

JAMES TRIPLETT, OF CAMPBELLSVILLE, KENTUCKY.

FIRE-ESCAPE.

SPECIFICATION forming part of Letters Patent No. 728,145, dated May 12, 1903.

Application filed March 20, 1903. Serial No. 148,711. (No model.)

To all whom it may concern:

Be it known that I, JAMES TRIPLETT, a citizen of the United States, residing at Campbellsville, in the county of Taylor and State 5 of Kentucky, have made certain new and useful Improvements in Fire-Escapes, of which the following is a specification.

My invention is an improvement in fire-escapes, and has for an object to provide a simple construction which can be readily applied to a door, window, or other support in or adjacent to a room and by which a person can safely descend to the ground by means of a rope or cable and in doing so will elevate another rope or cable, so a second person can descend, who in turn will raise the first rope, so that an unlimited number of persons can escape by alternately using the two ropes with which the apparatus is supplied; and the 15 invention consists in certain novel constructions and combinations of parts, as will be hereinafter described and claimed.

In the drawings, Figure 1 is an elevation of the fire-escape apparatus as in use. Fig. 2 is a detail front elevation of the fire-escape. Fig. 3 is a detail cross-section on about the line 3 3 of Fig. 2, showing the gearing and the 20 brake mechanism; and Fig. 4 is a detail perspective view illustrating the means for adjusting the drums on the shafts to adapt the escape for use at different heights.

In carrying out my invention I provide a suitable frame consisting of the parallel plates A and B, suitably braced in position by the 25 connecting-bolts C and provided with the eyes D for receiving screws or with other suitable devices to facilitate securing the frame to a door, window, or other suitable support in or adjacent to the room whose occupants it is 30 desired to protect by the fire-escape. The frame also includes the brackets E, extending outwardly from the plates A and B and provided at their outer ends with bearings at e for the main shaft F of the apparatus. This 35 shaft F journals near its ends in the bearings e and is also journaled in bearings a and b in the frame-plates A and B and is provided adjacent to the inner side of the plate B with a gear-wheel G, which meshes with the pinion H on the counter-shaft I, which counter-shaft 40 I is also provided with a gear-wheel J, meshing with the pinion K on the fan-shaft L,

which is provided with a fan-plate M to operate as a brake, as its shaft is rapidly revolved as the person descends.

The shaft F is provided between the plates A and B and their respective brackets E with the drums N and O, which are alike and loose on the shaft and which have their inner heads provided with the studs n to enter seats P' 55 in disks P, secured on the shaft F close to the outer sides of the plates A and B, springs Q being arranged to press the drums into engagement with their respective disks P, so as to hold the drums normally in engagement 60 with the said disks P and at the same time permit the disengagement of said drums from their disks in order to let out more or less rope from the drums to adapt the escape to buildings of different heights. The operation 65 of this construction will be readily understood from the drawings, Fig. 4, and the foregoing description.

The ropes Q' are wound on their respective drums N and O in reverse directions, so that 70 as one rope descends the other will ascend, carrying with it the loop-belt, basket, car, or other appliance, which may be applied to the ropes or cables to receive the escaping persons. By this means as one person descends in escaping on one cable the other cable 75 will be raised to the others in danger, so they can escape one by one.

By means of the device for adjusting the lengths of the cables, as before described, 80 they can be caused to raise the cables to the proper height to receive the escaping persons.

A bar R is looped around the counter-shaft I and is provided with a depending rope or cable, so it can be operated from the ground 85 to serve as a brake while the escaping person is getting out of the window.

The cables are guided below the plates A and B by means of a metal guide-frame S, consisting of a length of metal rod passed 90 through openings at T in the plates A and B, so the frame can swing at its lower end and having its depending portions crossed below the plates A and B and provided at their free ends with guide-loops S' for the ropes or cables.

It will be understood that the apparatus, except the cables, may be made of metal and that the cables may be made of fireproof ma-

terial or may be coated with fireproof mate-
rial, so that they will not be destroyed by
flames escaping from the window or other
opening in the path of the cables.

5 Having thus described my invention, what
I claim, and desire to secure by Letters Pat-
ent, is—

1. The improved fire-escape herein de-
scribed comprising the framing having the
10 main plates provided with bearings for the
main shaft, devices connecting said plates
and holding same properly apart, the later-
ally-projecting brackets on the main plates
provided at their outer ends with bearings for
15 the main shaft, the main shaft journaled in
the plates and brackets and provided between
the plates with a gear-wheel and between
the plates and brackets, and adjacent to
the plates, with the disks having openings
20 for the studs on the drums, the drums loose
on the shafts and having their inner heads
provided with studs to enter the openings
in the disks on the shaft, the springs for
forcing the drums into engagement with their
25 respective disks, the counter-shaft having a
pinion meshing with the pinion on the main
shaft, the gear on the counter-shaft, the brake-

shaft having the pinion meshing with the
gear on the counter-shaft, the fan-plate on
the brake-shaft, the brake-rod looped around 30
the counter-shaft, and the guide-frame in the
form of a rod swinging from the main plates
and crossing below the same and provided
with guide-loops adapted to receive the ca-
bles depending from the drums, all substan- 35
tially as and for the purpose set forth.

2. The combination in a fire-escape of the
framing having the main plates and the out-
lying brackets, said brackets and plates hav-
ing bearings for the main shaft, the drums 40
loose on the main shaft between the plates
and the brackets, the disks fixed on the shaft
between the drums and plates and arranged
for engagement with the drums, the springs
for holding the drums normally in engage- 45
ment with the disks, the cables wound in re-
verse directions on the drums, and guide de-
vices suspended from the plates for said ca-
bles, substantially as set forth.

JAMES TRIPLETT.
